RADIO-FREQUENCY ROTATING JOINT

Donald W. Peterson, Princeton, N. J., assignor to
 Radio Corporation of America, a corporation
 of Delaware

Application July 14, 1943, Serial No. 494,617

4 Claims. (Cl. 178—44)

1

This invention relates to radio frequency distribution systems and more particularly to improvements in rotatable couplings or joints for concentric transmission lines used for transferring radio frequency energy between a rotatable antenna and a fixed transmitter or receiver.

In the operation of directional radio devices it is frequently necessary or desirable to rotate the antenna continuously. This necessitates a rotatable coupling in the transmission circuit between the antenna and the radio apparatus. One prior art type of rotatable coupling comprises a pair of concentric line sections, with outer conductors and inner conductors respectively coupled through slidable spring fingers, thus providing conductive coupling between the two transmission line sections. One disadvantage of such an arrangement is that the contacts tend to become erratic through wear caused by continuous use with the result that arcing may cause them to destroy themselves. Also small particles of material become dislodged and fall into the bearings and the space between the inner and outer line conductors. An accumulation of such particles is likely to cause destructive arcing across the line, particularly where large peak power is being transmitted.

Some prior art devices avoid the above mentioned difficulties but introduce undesirable frequency characteristics, as described more fully hereinafter.

It is the principal object of this invention to provide an improved rotatable coupling for radio frequency transmission lines.

Another object is to provide an improved coupling of the described type embodying no movable or slidable contacts.

A further object is to provide a coupling which will operate efficiently over a broad band of radio frequencies. These and other objects will become apparent to those skilled in the art upon consideration of the following description, with reference to the accompanying drawing, of which

Figure 1 is a schematic diagram of one type of prior art coupling.

Figure 2 is a schematic diagram of a rotatable joint according to the present invention, and

Figure 3 is a longitudinal section of a rotatable joint embodying the principles illustrated by Fig. 2.

Referring to Fig. 1, a known type of rotatable joint involving no slidable contacts is shown. Two concentric line sections 1 and 3 are arranged so that their inner conductors and outer conductors respectively overlap by a distance d .

2

The diameter of the outer conductor 5 of the line 1 is slightly less than that of the outer conductor 7 of the line 3, so that the conductors 5 and 7 are closely adjacent to each other but do not touch throughout the overlapping portion. The inner conductor 9 of the line 1 is hollow at least through the overlapping portion, having an inner diameter slightly greater than the diameter of the inner conductor 11 of the line 3.

10 The operation of the above described structure is as follows:

The overlap d is adjusted to approximately $\frac{1}{4}$ wavelength at the frequency at which the equipment is to operate. The overlapping outer conductors 5 and 7 constitute a low impedance concentric line, open-circuited at its outer end 13. Owing to the well known impedance inversion characteristics of $\frac{1}{4}$ wave lines, the open circuit at the point 13 is reflected as a short circuit at the point 15, thus effectively connecting together the outer conductors 5 and 7 at this point. Similarly the inner conductors 9 and 11 act as a $\frac{1}{4}$ wave line open circuited at the point 17 and present a short circuit at the point 19. Thus at the frequency for which d is equal to a $\frac{1}{4}$ wavelength, the inner conductors 9 and 11 are effectively connected together at the point 19. If the clearances between the overlapping portions of the conductors of the lines 1 and 3 are relatively small, the characteristic impedances of the $\frac{1}{4}$ wave open circuited lines are relatively low, and the impedance presented at the points 15 and 19 are substantially zero over a fairly wide frequency range. A typical joint constructed according to Fig. 1 is capable of transferring energy to a matched line over a range of 300 to 500 megacycles with a standing wave ratio of 85 percent or better over a range of 1.67 to 1.

According to the present invention a usable 40 frequency range of the order of three to one is obtained by spacing the series reactances of the low impedance sections formed by the overlapping conductors so that reactance cancellation occurs at two frequencies respectively above and 45 below the midband frequency. Referring to Fig. 2, the lines 1 and 3 are arranged with their conductors in overlapping relationship as in the system of Fig. 1. The outer conductors 5 and 7 and the inner conductors 9 and 11 overlap by distances d , where d is approximately $\frac{1}{4}$ wavelength near the center of the frequency band over which the system is to operate. The overlapping portion of the outer conductors 5 and 7 is separated from the overlapping portion of the 50 inner conductors 9 and 11 by a distance which

is the distance from point 15 to point 19 and is somewhat greater than a $\frac{1}{4}$ wavelength at the midband frequency.

The operation of the above described coupling at the midband frequency is substantially identical to that of the structure of Fig. 1. The open circuits at points 13 and 17 are reflected as short circuits at points 15 and 19, effectively connecting the outer conductors 5 and 7 and the inner conductors 9 and 11 respectively. At frequencies below the midband frequency, the overlapping conductors present capacitive reactances at points 15 and 19. The line section of length s between the points 15 and 19 inverts the capacitive reactance at the point 15 to inductive reactance at the point 19, tending to cancel the capacitive reactance presented at the point 19 by the line comprised of conductors 9 and 17. At some frequency below the midband frequency this cancellation is complete, providing no mismatch in the connection between the lines 5 and 7. Similarly at frequencies higher than the midband frequency, inductive reactances are presented at points 15 and 19, and inversion by the line section between those two points tends to cause reactance cancellation and provides a complete match at some one frequency above the midband frequency. By proper adjustment of the displacement between the overlapping portions of the inner and outer conductors, the frequencies at which reactance cancellation takes place may be selected so as to provide substantially perfect matching over a wide frequency band. A typical joint constructed in accordance with Fig. 2 will transmit energy over a frequency range of 175 to 600 megacycles with a standing wave ratio of 85 percent or better, or substantially twice the band width over which the arrangement of Fig. 1 will provide equivalent operation.

Fig. 3 shows one form of mechanical construction of a joint of the type schematically illustrated in Fig. 2. A tubular conductive member 21 is supported in bearings 23 and 25 within a housing 27. One end of the tubular member 21 terminates in a threaded fitting 29 for connection to the outer conductor of a rotatable coaxial transmission line, not shown. The other end of the member 21 extends concentrically within a second tubular conductive member 31, which is secured at one end to the housing 27 by means of a flanged member 33 and a disk 34 of insulating material, and is provided at its other end with a threaded fitting 35 for engagement with the outer conductor of a stationary coaxial transmission line, not shown. The ends of the members 21 and 31 adjacent the fittings 29 and 35 contain insulating material for supporting concentric inner conductors 37 and 39 respectively. The conductor 37 is provided with a rod-like extension 41 which may be formed integrally therewith and extends along the axis of the member 21. The conductor 39 is secured, by soldering or the like, at the point 43 to a tubular conductor 45, which extends over the rod 41 and is supported thereon by insulators 47 and 49. The conductors 37 and 39 are provided at their outer ends with fittings 51 and 53 for connection to the inner conductors of coaxial transmission lines. In operation, the line connected to the members 29 and 51 is rotated about its axis, while the housing 27 and the line connected to the members 35 and 53 remains stationary. The overlaps d between the conductors 21 and 31 and the conductors 41 and 45 and the spacings between the overlapping portions

are proportioned as described above in connection with Fig. 2.

Thus the invention has been described as an improved rotatable joint for radio frequency transmission lines providing efficient transfer of energy over a band of frequencies without the use of sliding metallic contacts. The inner and outer conductors of the sections to be joined overlap by substantially a $\frac{1}{4}$ wave length in the middle of the band to be transmitted, providing a perfect match at that frequency. The overlapping portion of the outer conductors is longitudinally spaced from that of the inner conductor, providing reactance cancellation and substantially perfect matching at two frequencies respectively above and below the midband frequency.

I claim as my invention:

1. A joint for connecting a rotatable coaxial transmission line to a stationary transmission line, including a pair of concentric tubular conductive members disposed in radially spaced overlapping relationship to each other and insulated from each other and adapted to be connected to the respective outer conductors of two coaxial lines, a second pair of concentric conductive members disposed coaxially within said first pair of conductive members in radially spaced overlapping relationship to each other and insulated from each other and from said first pair of conductors, the overlapping portion of said second pair of conductive members being by a distance of approximately one-quarter wavelength at the center of the band of frequencies over which the device is to operate spaced longitudinally along the axis of said lines from the overlapping portion of said first pair of conductive members by a distance somewhat greater than the length of said overlapping portions and substantially less than twice said length.
2. A device of the class described, including a pair of concentric radially spaced, overlapping outer conductors insulated from each other, a pair of concentric radially spaced overlapping inner conductors insulated from each other and from said outer conductors, the lengths of the overlapping portions of said conductors being such as to present substantially zero reactances to currents of a predetermined frequency, and capacitive and inductive reactances to currents of frequencies respectively below and above said predetermined frequency, said overlapping portions being spaced longitudinally of said device to provide impedance inversion and substantial cancellation of said reactances at two predetermined frequencies respectively above and below said predetermined frequency.
3. A device of the class described, comprising a pair of concentric tubular conductors disposed in radially spaced overlapping relationship and insulated from each other, a second pair of concentric radially spaced overlapping conductors disposed within said first pair and coaxially therewith and insulated from each other and from said first pair of conductors, with the overlapping portion of said second pair of conductors spaced longitudinally from the overlapping portion of said first pair by a distance substantially less than one quarter wave length at the center frequency of the band of frequencies over which the device is to operate, the length of each of said overlapping portions being approximately one-quarter wave length at said center frequency.
4. A device of the class described, comprising a pair of concentric tubular conductors disposed in radially spaced overlapping relationship and

insulated from each other, a second pair of concentric radially spaced overlapping conductors disposed within said first pair and coaxially therewith and insulated from each other and from said first pair of conductors, with the overlapping portion of said second pair of conductors spaced longitudinally from the overlapping portion of said first pair, the lengths of said overlapping portions being approximately one-quarter wave length at the center of the band of frequencies over which the device is to operate, corresponding points on said overlapping portions being spaced longitudinally by a distance somewhat greater than the length of said overlapping portions and substantially less than twice said length.
